METAL HAMMERING APPARATUS

Louis Levine, New York, N. Y.

Application December 9, 1939, Serial No. 308,420

3 Claims. (Cl. 101—3)

This invention relates generally to a method and apparatus for hammering designs on metal against a die, but more specifically to a method and apparatus for running an automatically operated hammer over areas of a plate exposed through a template, the opposite sides of said exposed areas abutting a die.

Heretofore in the manufacture and production of hand-hammered trays, and other metal-ware, one method of producing designs thereon included the hammering by hand of an area of one side of the plate, the opposite side contacting a die with a design engraved thereon. In this process, the operator wielding the hammer was compelled to repeat hammer strokes over the plate area above the die containing the engraved design until the design was impressed on the plate. In this practice, it was found that the plate portions adjacent the design areas were distorted, bent and otherwise misshapen, thereby necessitating a straightening operation following the hammering out of the design. Moreover, the number of hammered designs which an operator could complete was dependent upon the speed and skill of the operator in wielding his hammer.

The present invention, therefore, has as its main object the production of designs from a die by means of an automatically driven hammer manually guided over openings in a template securing the metal to be designed over the die.

A further object of the invention resides in the provision of a method and apparatus for manufacturing plateware having hammered designs thereon wherein speed of production is accelerated and labor costs are reduced.

These objects and other incidental ends and advantages of the invention will hereinafter appear in the progress of the disclosure and as pointed out in the appended claims.

Accompanying this specification are drawings showing a preferred form of the invention wherein corresponding reference characters designate corresponding parts throughout the several views and wherein:

Figure 1 is a top plan view showing securing means for fixing a plate between an orificed template and an engraved die, the orifices of the template affording operating areas over which an automatically operated hammer is normally guided.

Figure 2 is a front view in elevation of Figure 1.

Figure 3 is a fragmentary end view in elevation showing locking means of the plate to be designed between the template and the die.

Figure 4 is a sectional view of Figure 1 along 53

the plane 4—4 thereof showing also an automatically driven hammer within an orifice of the template.

Figure 5 is an end view in elevation of a plate adapted to be secured within the apparatus and operated upon by the process described herein.

Figure 6 is a view similar to Figure 5 showing a design impressed on the undersurface of the plate by means of the process and apparatus hereinafter to be described.

In the preferred embodiment of the invention, a metal bed 10 is preferred to serve as a non-vibrating base for a template frame generally designated by numeral 11, the said frame being secured to a template seat generally designated by numeral 13 by means of a pair of hinges 12. Seat 13 consists of a conventional framework having horizontal and transverse members, each of the horizontal members being designated by numeral 14, while each of the transverse members are designated by numeral 15, the said seat 13 being secured to bed 10 by means of bolts 17 penetrating lugs 16 extending from the horizontal members 14.

Fixed within the template seat framework is a die having any desired upper engraved areas 19, the said areas being contacted by a surface of a plate 20 adapted to have a design hammered thereon. The upper exposed surface of plate 20 is indicated by numeral 21 and the surface contacting die 18 is indicated by numeral 22. In order to center plate 20 over die 18, a pair of stops 23 and 24 are provided and are secured to members 15 and 14 of the template seat framework.

The template frame 11 hinged to template seat 13 is comprised of a framework having horizontal and transverse members, each of the horizontal members being designated by numeral 25 and each of the transverse members being designated by numeral 26. As shown, members 25 and 26 are narrower than the template seat members 14 and 15 within which latter the die plate 18 is nested. A pair of handles to raise and lock the template framework to the seat are provided and consist of levers 27 secured at the ends of the front horizontal member 25 at the upper surface thereof by means of pivots 28. Levers 27 project forwardly from member 25 and are provided with handles 30, each of the said levers at the projecting portions having a depending U member 31 adapted to engage a lug 29 situated at each end of horizontal member 14 at the front face thereof, the said lugs 29 being tapered at 32 to permit easy engagement by U members 31.

Spaced from the inner walls of the template frame members 25 and 26 is a template 33 adapted to contact die 18 and between which plate 20 is adapted to be secured. A plurality of spaced and parallel bars 34 secured to members 25 and the upper surface of the template 33 by means of screws 35 serve to connect the template 33 to the template framework. To avoid scratching of the surface of plate 20 by the undersurface of template 33, a lining 36 is secured to the underside of the template, the latter itself being provided with openings 37 and 38 to conform in shape with the engraved areas 19 of die 18.

Openings 37 and 38 of template 33 afford an area in which a motor or pneumatically driven hammer generally designated by numeral 39 is adapted to be manually guided over the exposed portion of plate 20 through said openings whereby impressions are made on the opposite side of plate 20 off the engraved designs of die 18. The hammer is comprised of the usual parts such as a round headed reciprocating plunger 40 having a guide 41, a motor 42 and handles 43. To aid the operator, the hammer may be suspended or counterbalanced from the ceiling so that in wielding the same, the operator is not subjected to the full weight thereof and is in a position to easily transverse the exposed area of plate 20 through openings 37 and 38.

In operating the apparatus, handles 30 are drawn outwardly whereby lugs 29 on the template seat are disengaged and the template framework 11 is swung back on hinges 12. Thereafter, plate 20 upon which a design is adapted to be impressed is centered over die 18 within the template seat framework by passing said plate thereabove between stops 23 and 24. Following the centering of plate 20 over die 18, the template 33 and its framework are lowered on hinges 12 and secured to the template seat by drawing handles 30 toward each other. Thereafter, the operator wields the automatically driven hammer 39 within openings 37 and 38 of template 33 whereby a plurality of hammer strokes are equally distributed within the borders of openings 37 and 38 of template 33 thereby impressing designs on the undersurface of plate 20 adjacent die 18 without affecting the surface of plate 20 adjacent the exposed areas. When this procedure has been completed, the template frame is raised from the template seat by unlocking handles 30 and the engraved plate 20 removed.

It is to be observed that the process above described is applicable to any shape of plateware 55

and that die 18, the template frame and seat may all be correspondingly changed in shape and design to meet desired demands.

I wish it understood that minor changes and variations in the material, integration of parts, shape and size thereof, may all be resorted to without departing from the spirit of the invention and the scope of the appended claims and that minor variations in the steps of the process hereinbefore described, may also be resorted to without departing from the spirit of the invention and the scope of the appended claims.

I claim:

1. Apparatus for manufacturing hammered designs on metalware against a die, including a non-vibrating horizontal bed, a framework supported thereon and having a die mounted centrally thereof, a second framework pivotally secured to the first mentioned framework and carrying a central and orificed template, said die having engraved designs opposite the template openings, releasable closure means between the two frameworks, guiding means associated with the first mentioned framework to secure a piece of metalware centrally over the die whereby upon closure of the second framework the said piece of metalware on the undersurface abuts the die and on the upper surface abuts the template.

2. Apparatus for manufacturing hammered designs on metalware against a die including a non-vibrating horizontal bed, a framework supported thereon and having a die mounted centrally thereof, a second framework pivotally secured to the first mentioned framework and carrying a central and orificed template, the said die having engraved designs opposite the template openings, means pivoted to the second framework and releasably engageable with the first framework to lock a piece of metalware between the template and the die.

3. An apparatus for manufacturing hammered designs on metalware between a template and die by means of a pneumatically driven tool, including a non-vibrating horizontal bed, a framework supported thereon and having a die mounted centrally thereof, a second framework pivotally secured to the first mentioned framework and carrying an orificed template through which the tool is adapted to operate, the said die having engraved designs opposite the template openings, releasable locking means between the frameworks to secure a piece of metalware between the template and the die.

LOUIS LEVINE.
